TRANSPORT TRUCK FOR CIRCUIT BREAKER UNITS

Glen L. Claybourn, Pittsburgh, Pa., assignor to
Westinghouse Electric Corporation, East Pittsburgh, Pa., a corporation of Pennsylvania

Application December 22, 1951, Serial No. 262,979

10 Claims. (Cl. 214—38)

1

My invention relates, generally, to metal enclosed switchgear and, more particularly, to trucks for transporting circuit breaker units externally of the stationary housings for the breaker units.

Outdoor metal enclosed switch houses are usually installed with the floor of the house several inches above the surface of the concrete base pad. Steel rails are provided in the housing for the wheels on the movable circuit breaker unit. It is necessary to provide a transport truck having rails thereon which are at substantially the same elevation as the rails in the housing to permit the breaker unit to be transferred easily from the truck to the housing or vice versa.

Normally, the concrete floor settles below the structural steel in the base pad. The structural steel is levelled and is the mounting surface for the housing structure. Since the transport truck rests on the concrete floor, differences in elevation may exist between the rails on the truck and the rails in the housing, thereby making it difficult to insert or remove the circuit breaker unit.

An object of my invention, generally stated, is to provide a circuit breaker transport truck which is simple and efficient in operation and which may be economically manufactured.

A more specific object of my invention is to provide for adjusting a transport truck to compensate for differences in elevation between the rails in the steel housing structure and the concrete floor, thereby permitting the alinement of the rails on the truck with the rails in the stationary housing.

Another object of my invention is to provide means for retaining the circuit breaker unit on the truck during the transport operations.

A further object of my invention is to provide means for securing the transport truck to the housing while transferring the breaker unit from the truck to the housing or vice versa.

Still another object of my invention is to provide a common actuating means for both the breaker unit retaining means and the truck securing means.

A still further object of my invention is to prevent tilting of the transport truck while transferring the breaker unit.

Other objects of my invention will be explained fully hereinafter or will be apparent to those skilled in the art.

In accordance with one embodiment of my invention the rear wheel axle of a transport truck may be adjusted vertically by means operable from in front of the truck. The breaker unit

2

is retained on the truck, while being transported, by a latch operable from in front of the truck. The truck may be secured to the housing, while the breaker unit is being transferred from the truck to the housing or vice versa, by latch means also operable from in front of the truck. Rail guide and weight bearing extensions are provided on the rear of the truck to extend into the housing, thereby aligning the rails on the truck with the rails in the housing and preventing tilting of the truck while transferring the breaker unit.

For a better understanding of the nature and objects of the invention, reference may be had to the following detailed description, taken in conjunction with the accompanying drawings, in which:

Figure 1 is a view, in plan, of a transport truck embodying the principal features of the invention;

Fig. 2 is a view, in front elevation, of the truck shown in Fig. 1;

Fig. 3 is a view, in longitudinal section, taken along the line III—III of Fig. 1;

Fig. 4 is a detail view, in plan, of a portion of the truck and housing structures, and

Fig. 5 is a reduced view, in plan, of one of the members of the truck.

Referring to the drawings, and particularly to Fig. 1, the structure shown therein comprises a transport truck 10 and a portion of a metal clad switchgear unit housing 11 which is shown by broken lines. The housing 11 may be of a type suitable for outdoor service and comprises upright members 12 disposed at the front corners of the housing and having side sheets 13 attached thereto. Spaced rails 14 are provided on the floor of the housing for the wheels of a removable circuit breaker unit 15, see Fig. 3, which may be transported externally of the housing by means of the truck 10. As shown in Fig. 3, the circuit breaker unit 15 rests upon the truck 10 while it is being transported to and from the housing 11.

As shown most clearly in Fig. 3, the transport truck 10 comprises a base 16 having a downwardly extending flange 17 around the base. The base 16 is supported by a wheel axle 18 having wheels 19 mounted thereon at the rear end of the base and swivel wheels 21 at the front end of the base. The wheels 21 are mounted in swivels 22 which are attached to a flanged channel member 23 by means of bolts 24. The channel member 23 may be welded to the bottom side of the base 16 or secured thereto in any other suitable manner.

A generally Z-shaped stop member 25, which extends across the base 16, may be welded to the top side of the base near the front end. The top of the Z member 25 has a downwardly extending flange 26. A maneuvering handle 27, which may be a round bar or pipe formed into a U shape, may be welded to the front flange 17 of the base 16 and also to the flange 26 on the Z member 25, thereby providing a means for moving the truck 10 where desired.

The truck 10 is provided with rails 37 for the wheels of the breaker unit 15. As shown in Fig. 1, the rails 37 are spaced apart the same distance as the rails 14 in the housing 11. The rails 37 extend rearwardly beyond the base 16 into the housing 11 when the truck 10 is in position in front of the housing. In order to insure that the truck will be in its proper position for transferring the breaker unit to or from the truck, a guide plate 38 is provided at the outer side of each rail 37. The plates 38 extend rearwardly beyond the ends of the rails 37, and the inner side of each plate has a sloping surface 39 which will engage the outer side of one of the rails 14 in the housing to insure that the truck 10 is properly positioned in front of the housing 11. Since the rails 37 and the guide plates 38 extend into the housing 11 over the floor of the housing, they will support the weight of the breaker unit as it is being transferred to or from the truck 10, thereby preventing the truck from tilting under the weight of the breaker unit as the transfer is being made.

In order to secure the truck 10 in its proper position in front of the housing 11 while a transfer is being made, a latch 31 is provided for engaging each one of the upright members 12 at the sides of the housing 11. Each latch 31 may be actuated by a handle 32 disposed at the front corner of the truck 10. The handle 32 is secured to one end of a shaft 33 and the latch 31 is secured to the other end of the shaft 33. The shaft is rotatably mounted in sleeves 34, one of which is welded to a supporting bracket 35 at the rear of the truck. The other sleeve 34 is welded to a plate 36 which is bolted to the Z member 25 at the front of the truck. Thus, the latches 31 may be operated from in front of the truck 10 to engage the housing 11, thereby retaining the truck in position in front of the housing while a transfer of the circuit breaker unit is being made.

As shown most clearly in Fig. 4, latches 41 are provided for retaining the circuit breaker unit 15 on the truck 10 while it is being transported. As shown in Figs. 1 and 4, a latch 41 may be welded to each one of the shafts 33. The latches 41 are so disposed on the shafts 33 that they will engage corners of the breaker unit 15 when the latches are rotated 180° from the position shown in Fig. 1 to the position shown in Fig. 4. Each latch 41 may be actuated by means of one of the handles 32 secured to one of the shafts 33. It will be seen that the latches 31 are disengaged from the upright members 12 in the housing 11 when the latches 41 engage the breaker unit. Likewise, the latches 41 are disengaged from the breaker unit when the latches 31 engage the housing. In this manner, the breaker unit is prevented from rolling forwardly on the truck by the stop member 25 and it is prevented from rolling rearwardly by the latches 41 while the breaker unit is being transported on the truck 10. When the latches 41 are disengaged, the latches 31 are engaged to attach the truck to the housing to permit the breaker unit to be transferred from the truck to the housing or vice versa.

As explained hereinbefore, it is essential that the rails 37 on the truck be at substantially the same elevation as the rails 14 in the housing 11 while a transfer of the breaker unit is being made. 5 As also explained hereinbefore, it has been found that the floor portion of the concrete base pad which surrounds the steel framework on which the switchgear housing unit rests may settle varying amounts with respect to the steel framework, 10 thereby making it desirable to provide for adjusting the elevation of the rear end of the truck 10. In order that this adjustment may be readily made, the rear axle 18 may be raised or lowered with respect to the base 16, thereby varying the 15 elevation of the rear end of the base.

As shown most clearly in Fig. 3, the axle 18 is secured near the junction point of the two legs of an angle bar 46. The horizontal leg of the bar 46 is pivotally attached to the flange 17 of the 20 base 16 and the vertical leg of the bar 46 may be swung about the pivotal support for the bar, thereby moving the axle 18 in an arc about the pivotal support. The bar 46 is attached to the flange 17 by means of an angle bar 47 which may 25 be welded to the flange 17.

A detailed view of the member 46 is shown in Fig. 5. As shown, the horizontal leg of the bar 46 has two spaced notches 48 therein. Round bars 49 extend across the notches 48 and may be 30 welded to the horizontal leg of the bar 46. As shown in Fig. 3, each one of the bars 49 is attached to the horizontal leg of the angle bar 47 by means of a clip 51 and bolts 52.

As also shown in Fig. 5, the vertical leg of the 35 bar 46 has a notch 53 therein. A round bar 54 extends across the notch 53 and is welded to the vertical leg of the bar 46. As shown in Fig. 3, an angle bar 55 is slidably mounted on the bottom 40 side of the base 16. The bar 55 may be supported by pins 56 disposed in grooves 57 provided in the horizontal leg of the bar 55. As shown, the vertical leg of the bar 55 has a notch 58 therein for the bar 54 on the angle bar 46.

A plate 59 is welded to the angle bar 55 near the front end of the bar and a nut 60 is welded to the plate 59. The nut 60 is threaded for receiving a screw 61. The screw 61 is rotatably mounted in bearings 62 and 63. The front bearing 63 may be bolted to the flange 17. The U-shaped member 23 is notched at 64 to permit the screw to pass through the member 23. The rear bearing 62 comprises two spaced plates 65 which are attached to an angle bar 66 by bolts 67. A sleeve 68 may be welded to the screw 61 and disposed between the plates 65 to function as a thrust bearing for the screw 61. A replaceable washer 69 may be provided between the sleeve 68 and the one plate 65. Spacing sleeves 70 are provided on the bolts 67 between the plates 65.

As shown in Figs. 1 and 3, a T handle 71 may be inserted through an opening 72 in the front flange 17 of the base 16 onto the front end of the screw 61. A pin 73 is provided near the end of the screw 61 and is engaged by the sides of a notch 74 in the end of the handle 71. Thus, the screw 61 may be rotated in either direction by means of the handle 71 to move the angle bar 55 longitudinally of the base 16, thereby actuating the angle bar 46 about its pivotal support to move the axle 18 in an arc about the pivotal support for the angle bar 46. In this manner the rear end of the base 16 may be raised or lowered a predetermined amount, as shown by the arrows at 75, to adjust the elevation of the rear end of the base to compensate for variations in the

height of the floor portion of the concrete base pad upon which the truck 10 rests. As shown at 16 in Fig. 2, the swivel wheels 21 are mounted slightly lower than the normal or midposition of the rear wheels 19, thereby leaving the base 16 substantially level and making it unnecessary to push the breaker unit uphill while it is being inserted into the housing after the rear end has been raised to compensate for settling of the concrete base pad.

From the foregoing description it is apparent that I have provided a circuit breaker transport truck which is relatively simple in structure and which is readily movable while supporting a circuit breaker unit. The truck may be secured in its proper position in front of a switchgear unit housing while transferring a breaker unit to or from the truck and the breaker unit may be retained on the truck by suitable latching means while it is being transported on the truck. The elevation of the rear end of the truck may be readily adjusted to compensate for differences in elevation between the stationary structure rails and the floor upon which the truck rests. All the adjusting means, as well as the latching means for securing the truck in position and for retaining the circuit breaker unit on the truck are operable from in front of the truck at the convenience of the operator.

Since numerous changes may be made in the above described construction and different embodiments of the invention may be made without departing from the spirit and scope thereof, it is intended that all the matter contained in the foregoing description or shown in the accompanying drawings shall be interpreted as illustrative and not in a limiting sense.

I claim as my invention:

1. A transport truck for a circuit breaker unit having wheels thereon and adapted to be transferred from the truck into a switchgear housing having spaced rails therein, said truck comprising a base, a wheel axle at the rear of the base, a swivel wheel at the front of the base, spaced rails on top of the base for the wheels on the breaker unit, a rail guide disposed on top of the base adjacent to and extending rearwardly beyond each rail on the base and beyond the wheel axle to engage the rails in the housing, and mechanical means disposed underneath the base for moving the axle relative to the base to vary the elevation of the rear end of the base and said rail guides.

2. A transport truck for a circuit breaker unit having wheels thereon and adapted to be transferred from the truck into a switchgear housing having spaced rails therein, said truck comprising a base, a wheel axle at the rear of the base, spaced rails on top of the base for the wheels on the breaker unit, a rail guide disposed on top of the base at the side of each rail, said rail guides having sloping sides extending rearwardly beyond the ends of the rails on the base and the end of the base to engage the rails in the housing, and mechanical means for raising and lowering said axle to adjust the elevation of the rear end of the base and said rail guides.

3. A transport truck for a circuit breaker unit adapted to be transferred from the truck into a switchgear housing, said truck comprising a base for supporting the breaker unit, a wheel axle at the rear of the base, mechanical means operable from in front of the base for raising and lowering the axle to adjust the elevation of the rear end of the base, latch means disposed at the

rear of the truck for engaging the housing to retain the truck in position for transferring the breaker unit from the truck into the housing or vice versa, additional latch means for engaging the breaker unit to retain it on the base, and common means for actuating both of said latch means.

4. A transport truck for a circuit breaker unit adapted to be transferred from the truck into a switchgear housing, said truck comprising a base for supporting the breaker unit, a wheel axle at the rear of the base, mechanical means operable from in front of the base for raising and lowering the axle to adjust the elevation of the rear end of the base, latch means disposed at the rear of the truck for engaging the housing to retain the truck in position for transferring the breaker unit from the truck into the housing or vice versa, additional latch means for engaging the breaker unit to retain it on the base, and common means for actuating both of said latch means, said common means being operable from in front of the truck.

5. A transport truck for a circuit breaker unit adapted to be transferred from the truck into a switchgear housing, said truck comprising a base for supporting the breaker unit, a wheel axle at the rear of the base, mechanical means operable from in front of the base for raising and lowering the axle to adjust the elevation of the rear end of the base, latch means disposed at the rear of the truck for engaging the housing to retain the truck in position for transferring the breaker unit from the truck into the housing or vice versa, additional latch means disposed substantially at the rear of the truck for engaging the breaker unit to retain it on the base, common means for actuating both of said latch means, and manually operable means disposed at the front of the truck for actuating said common means.

6. A transport truck for a circuit breaker unit adapted to be transferred from the truck into a switchgear housing, said truck comprising a base for supporting the breaker unit, a wheel axle at the rear of the base, mechanical means operable from in front of the base for raising and lowering the axle to adjust the elevation of the rear end of the base, latch means disposed at the rear of each side of the truck for engaging the housing to retain the truck in position for transferring the breaker unit from the truck into the housing or vice versa, additional latch means disposed substantially at the rear of each side of the truck for engaging the breaker unit to retain it on the base, and manually operable means disposed at each side of the front of the truck and connected to both of said latch means on each side for actuating said latch means.

7. A transport truck for a circuit breaker unit adapted to be transferred from the truck into a switchgear housing, said truck comprising a base for supporting the breaker unit, a wheel axle at the rear of the base, mechanical means operable from in front of the base for raising and lowering the axle to adjust the elevation of the rear end of the base, latch means disposed at the rear of each side of the truck for engaging the housing to retain the truck in position for transferring the breaker unit from the truck into the housing or vice versa, additional latch means disposed substantially at the rear of each side of the truck for engaging the breaker unit to retain it on the base, handle means disposed at the front of the truck for actuating said latch means, and

rotatable shafts connecting said handle means and said latch means, both of said latch means at one side of the truck being actuated by the same shaft.

8. A transport truck for a circuit breaker unit having wheels thereon, said truck comprising a base having rails thereon for the wheel on the breaker unit, a shaft rotatably mounted on the truck, a latch secured to the shaft above the base to engage the breaker unit to retain it on the base, and a housing engaging latch also secured to said shaft and spaced from said first-named latch, both of said latches being operable from in front of the truck by rotating the shaft.

9. A transport truck for a circuit breaker unit having wheels thereon, said truck comprising a base having rails thereon for the wheels on the breaker unit, spaced upright members secured at the ends of the base, a shaft rotatably mounted in said upright members, a latch member secured to said shaft and disposed substantially at the rear of the truck to engage the breaker unit to retain it on the base, and a housing engaging latch member also secured to said shaft at the rear of the truck, both of said latch members being operable from in front of the truck by rotating said shaft.

15

10

10. A transport truck for a circuit breaker unit having wheels thereon, said truck comprising a base having rails thereon for the wheels on the breaker unit, spaced upright members secured at the ends of the base, a shaft rotatably mounted in said upright members, a latch member secured to said shaft and disposed at the rear of the truck to engage the breaker unit to retain it on the base, and a housing engaging latch member also secured to said shaft, both of said latch members being operable from in front of the truck by rotating said shaft.
